UNITED STATES PATENT OFFICE

171,240

FOLDING CHAIR

John M. Wiegel, Oakland, Calif.

Application May 26, 1953, Serial No. 25,194

Term of patent 14 years

(Cl. D15—8)

To all whom it may concern:

Be it known that I, John Mason Wiegel, a citizen of the United States of America, residing at Oakland, California, have invented a new, original, and ornamental Design for Folding Chair, of which the following is a specification, reference being had to the accompanying drawing, forming a part hereof.

Fig. 1 is a perspective view of a folding chair in its open position, showing my new design;

Fig. 2 is a top plan view thereof;

Fig. 3 is a front elevational view thereof;

Fig. 4 is a side elevational view thereof taken from the right of Fig. 3;

Fig. 5 is a rear elevational view thereof;

Fig. 6 is a front elevational view thereof with the chair in its folded position;

Fig. 7 is a rear elevational view thereof with the chair in its folded position;

Fig. 8 is a side elevational view thereof with the chair in its folded position; and

Fig. 9 is a top plan view thereof with the chair in its folded position.

I claim:

The ornamental design for a folding chair, substantially as shown.

JOHN M. WIEGEL.
